CLAIM

The ornamental design for a sphere device, as shown and described.

DESCRIPTION

FIG. 1 is a perspective view showing the sphere device embodying the new design;

FIG. 2 is a front elevation view thereof;

FIG. 3 is a left side elevation view thereof;

FIG. 4 is a top plan view thereof;

FIG. 5 is a bottom plan view thereof;

FIG. 6 is a partial cross-sectional view along the line 6-6 of FIG. 5 looking in the direction of the arrows;

FIG. 7 is a front elevation view of a variation of the sphere device; and,

FIG. 8 is a left side elevation view thereof.

The broken lines in the drawing views are included for the purpose of illustrating unclaimed environment only, and forms no part of the claimed design.

1 Claim, 3 Drawing Sheets
